UNITED STATES PATENT OFFICE.

PETER NELSON, OF ROCKFORD, ILLINOIS, ASSIGNOR TO ROCKFORD WOOD-WORKING COMPANY, OF SAME PLACE.

DESIGN FOR A SEWING-MACHINE CABINET.

SPECIFICATION forming part of Design No. 35,178, dated October 8, 1901.

Application filed September 3, 1901. Serial No. 74,250. Term of patent 3½ years.

To all whom it may concern:

Be it known that I, PETER NELSON, a citizen of the United States, residing at Rockford, in the county of Winnebago and State 5 of Illinois, have invented and produced a new and original Design for Sewing-Machine Cabinets, of which the following is a specification, reference being had to the accompanying drawing, forming part thereof.

10 In the accompanying drawing is shown a perspective view of my improved design for sewing-machine cabinets.

The design consists in a sewing-machine cabinet substantially of the configuration 15 shown.

The sewing-machine cabinet comprises the top 1, cover 2, ends 3, and supporting-legs 4. The legs are curved and provided with en-

largements 5. Curved braces 6 connect the legs, and spindles 7 connect the braces with 20 the body of the cabinet.

The front of the cabinet is in three sections—a center section 8, a section 9, composed of drawers, and the section 10.

Having described my invention, what I 25 claim as new, and desire to secure by Letters Patent, is—

The design for a sewing-machine cabinet, substantially as herein shown and described.

In testimony whereof I have signed my 30 name to this specification in presence of two subscribing witnesses.

PETER NELSON.
